Primary Examiner — Philip S Hyder*Assistant Examiner* — Roselynne Cody(74) *Attorney, Agent, or Firm* — Breiner & Breiner, L.L.C.**CLAIM**

The ornamental design for a demolition tool, as shown and described.

DESCRIPTION

FIG. 1 is a perspective view of the demolition tool;
 FIG. 2 is a first end view of the demolition tool of FIG. 1;
 FIG. 3 is a second end view of the demolition tool of FIG. 1;
 FIG. 4 is a first side view of the demolition tool of FIG. 1;
 FIG. 5 is a second side view of the demolition tool of FIG. 1;
 and,
 FIG. 6 is a third side view of the demolition tool of FIG. 1.
